UNITED STATES PATENT OFFICE.

THOMAS N. RUSSELL, OF CHICAGO, ILLINOIS.

LEVERAGE MEANS FOR UNCOUPLING DEVICES.

Application filed September 10, 1923. Serial No. 661,823.

To all whom it may concern:

Be it known that I, THOMAS N. RUSSELL, a citizen of the United States of America, and a resident of Chicago, county of Cook, 5 and State of Illinois, have invented a new and useful Improvement in Leverage Means for Uncoupling Devices, of which the following is a specification.

This invention relates to means for un- 10 coupling railway cars and more especially to leverage devices for lifting the knuckle locks of ordinary couplings. Heretofore various forms of simple leverage and crank devices have been used, which devices are 15 sufficient within the customary range of weights, but there is a growing tendency to increase the size and weight of nearly all railway accessories including coupling devices, and this necessitates the employment of a 20 more powerful lock lifting device. Such an appliance must be adapted for ready operation with the heaviest couplers in use, at any time, and by one man alone. This is the need which is met by the device herein 25 set forth and claimed.

The main objects of the invention are to provide an uncoupling device to operate heavier knuckle locks than the prior devices are adapted for; to provide a knuckle lock 30 lifting leverage device having power multiplying means adequate to meet the needs in a wide range of service; to provide for compounding the lift lever in a manner adapted to retain approximately the old arrangement and position of coupling, main fulcrum 35 and handle, and also retain substantially the same old mode of manual operation; to provide a simple and unitary pluri-fulcrum plate or bracket for securing to the end of 40 the car to support the leverage members; and to provide such a device of few and easily made parts adapted for ready installation on any cars of the general style to which such devices are applied.

45 An illustrative embodiment of this invention is shown in the accompanying drawings, in which:

Figure 1 is a fragmentary plan view of a car end showing a coupler and also the uncoupling device to which this invention relates.

Fig. 2 is a fragmentary end view of the

lower part of the car body showing in front elevation the device herein referred to.

Fig. 3 is a front elevation of the lever supporting bracket and adjacent lever ends but with the cover plate removed.

Fig. 4 is a section on the line 4—4 of Fig. 3.

Fig. 5 is a section on the line 5—5 of Fig. 3.

Fig. 6 is a conventional diagram illustrating a modified construction and arrangement of the bracket and lever members.

In the construction shown in the drawings, the car 1 and coupling device 2, including the knuckle lock 3, are shown substantially in accordance with the present usual construction.

The principal member of the uncoupler or lock lifting means here shown is the leverage means 4—5 in the form of a compound lever fulcrumed at 6 and 7 on a common bracket 8 which serves also as a connector to hold the two simple levers 4 and 5 in effective relation to each other. Said bracket 8 is located in substantially the usual pivot 75 bracket position on the car end, and is bolted to the end sill of the floor frame, as indicated at the points 9. The upwardly facing fulcrum 7 for the primary lever 5 is located near the lower right hand corner of 80 bracket 8 and the downwardly facing fulcrum 6 for the secondary lever 4 is near the upper left hand corner. Fulcrum 6 is spaced apart vertically from fulcrum 7 sufficiently to receive between them the overlapping arms of levers 4 and 5, the former over the latter, as well shown in Fig. 3.

The lever 5 is of the so-called "first kind", the fulcrum 7 being between the load point 3 and the power point 10. The lever 4 is of the "second kind", the load point 11 being between the fulcrum 6 and the power point or handle 12. The multiplying power of the compounding feature is dependent on the relative spacing of the fulcrum points 6 and 7 from the point 11, where the upper lever 4 bears upon the lower lever 5, and this spacing is a matter of design depending upon other factors and upon the work to be done.

100 The bracket 8 may well be in the form of a casting and comprises an outstanding body part, and cover or face plate 13 removably secured by the fasteners 14. Said body part

has a vertical front face provided with a pair of vertically spaced horizontal ribs or spacer members 15 and 16, with a wide horizontal aperture 17 between for the overlapped ends of levers 4 and 5. Each rib is thickened medially to provide for the said fulcrums respectively which are formed integrally therewith. Each part 15 and 16 is formed and adapted to serve as a stop to limit the swing of the lever elements, as by stop contact at the points 15', 15'', 16', and 16''. The upper part is closed on the end at 15''. Each fulcrum part extends through a hole 13' in the plate 13 and the cotter keys 14 fit in holes therefor in the fulcrum tips as will be understood.

The aperture 17 is formed to permit limited vertical oscillation of said levers 4 and 5 but is formed to prevent lateral movement of the former lever, though the latter is permitted appreciable side play, as shown at 17', sufficient to accommodate normal car and coupler movements, by reason of the flare extending horizontally in both directions from fulcrum 7, as shown by Fig. 5. The power end 10 of the operating lever 5 is made with a wide bearing by bending the tip transversely so as to accommodate the lateral swing of lever 5 without disengaging the handle lever 4. The levers 4 and 5 are notched at 4' and 5' to receive their corresponding fulcrums, and these prevent endwise movement of the levers.

In order to remove either or both of the bars 4 and 5 the pintles 14 are withdrawn. This releases the face plate or cover 13 which may then be slid off from the fulcrum tips, thus freeing the levers 4 and 5 which may then be removed sidewise.

Referring to the modification shown by Fig. 6, it will be seen that the leverage means may be compounded somewhat differently. Here the primary lever or operating lever 18 is of the "third kind", the power point 19 being between the fulcrum 20 and the load or knuckle lock 3, and the secondary lever 21 is of the "first kind", the fulcrum 22 being between the power point or handle 23 and the load point 24. The operating lever 18 is above the other, but the power is multiplied in substantially the same manner as in Fig. 2.

Although only two specific embodiments of this invention are herein shown and described, it is to be understood that no attempt has been made to show all practical forms of embodiment and that some of the details of the constructions shown may be altered or omitted without departing from the spirit of this invention as defined by the following claims.

I claim:

1. An uncoupling device of the character described comprising in combination a power multiplying compound lever and a

bracket therefor having two fulcrums spaced apart diagonally in a vertical plane, said lever including one component lever of the first kind to engage the knuckle lock and another component lever of the second kind provided with a handle for manual operation, said component levers being mutually overlapped at said bracket between said fulcrums, and the second mentioned component lever being disposed over the other. 75

2. An uncoupling device of the character described comprising in combination a power multiplying compound lever and a bracket therefor having two fulcrums spaced apart diagonally in a vertical plane, said compound lever including a pair of simple levers disposed substantially in alignment but overlapping at said bracket where one of them, a handle bearing lever, is arranged to operate on the other, a knuckle lock engaging lever over and upon which it rests. 80

3. An uncoupling device of the character described comprising in combination a power multiplying compound lever and a bracket therefor having two fulcrums spaced apart diagonally in a vertical plane, said compound lever including a pair of simple levers disposed in opposite directions from said bracket where they overlap for mutual reaction, one directly over the other, one being fulcrumed to operate as a lever of the first kind and the other being fulcrumed to operate as a lever of another kind. 90

4. An uncoupling device of the character described comprising in combination a power multiplying compound lever and a bracket therefor having two fulcrums spaced apart diagonally in a vertical plane, said compound lever including a pair of simple levers disposed in opposite directions from said bracket where they overlap for mutual reaction, one over the other, one being fulcrumed to operate as a lever of the first kind and the other being fulcrumed to operate as a lever of another kind, and said fulcrums being disposed the upper to the left and the lower to the right as normally viewed. 100

5. An uncoupling device of the character described comprising in combination a compound lever and a bracket therefor having two fulcrums spaced apart diagonally in a vertical plane, said compound lever including a pair of simple levers disposed to extend in opposite directions from said bracket where they overlap for mutual reaction, one over the other, one of said simple levers having a handle arm and the other having an operating arm, said bracket being formed to limit side play for the former lever and being flared horizontally from the fulcrum of the latter lever to accommodate normal car and coupler movements without binding the operating lever. 115

6. An uncoupling device of the character 130

described comprising in combination a compound lever and a bracket-like member which is apertured to receive the overlapping ends of the lever elements, which elements extend oppositely each in approximately a horizontal position, said member having transversely disposed fulcrums for said elements respectively, which elements

are notched on appropriate edges respectively to receive said fulcrums, whereby 10 endwise movement of said elements normally is positively prevented.

Signed at Chicago this 7th day of September 1923.

THOMAS N. RUSSELL.
